UNITED STATES PATENT OFFICE.

ALBERT T. MARSHALL, OF HARTFORD, CONNECTICUT, ASSIGNOR TO AUTOMATIC REFRIGERATING COMPANY, OF HARTFORD, CONNECTICUT, A CORPORATION OF NEW JERSEY.

REFRIGERATING APPARATUS.

1,425,265.

Specification of Letters Patent. Patented Aug. 8, 1922.

Application filed October 29, 1919. Serial No. 334,286.

To all whom it may concern:

Be it known that I, ALBERT T. MARSHALL, a citizen of the United States, residing at Hartford, county of Hartford, and State of Connecticut, have invented certain new and useful Improvements in Refrigerating Apparatus, of which the following is a specification.

This invention relates to refrigerating apparatus in which the refrigerant in a gaseous state, is compressed into a fluid condition and then expanded under reduced pressure to absorb heat as it returns from the fluid state to a gaseous condition. The object of this invention is to provide improved apparatus for controlling the refrigerating process by means of the variation in pressure of the refrigerant in its expanded condition. One of the objects of the present invention is to provide improved means for utilizing the relative variations in pressure in the refrigerating coil and thermostatic chamber provided therefor, for securing greater efficiency and economy of operation. Other and more specific objects of invention will appear in the specification and be pointed out in the appended claims, reference being had to the accompanying drawings which show an adaptation of my invention.

In the drawings:—

Figure 1 is a diagram of a refrigerating apparatus constructed in accordance with the principles of the present invention.

Figure 2 is a vertical section on an enlarged scale, of the fluid pressure control switch, parts being shown in elevation.

Figure 3 is an enlarged scale section and side elevation of the motor operated valve.

Figure 4 is an axial section on an enlarged scale, of a preferred form of expansion valve parts being shown in elevation.

Referring more particularly to the drawings in the embodiment of my invention shown therein, a motor 1 is connected by a belt 2 with a wheel 3 which is keyed to a counter-shaft 4 which carries a pulley 5, said pulley 5 being connected by a belt 6 with the fly wheel 7 which is keyed to a compressor shaft 8. Said compressor is provided with a cylinder 9 from which a pipe 10 leads to a condenser 11, said condenser discharging through a pipe 12 into a receiver 13 for the condensed refrigerant.

Leading from the receiver 13 is a pipe 14 which may be made of suitable size and capacity to supply any desired number of refrigerating units of which only two are shown on the drawings. Said units with their connections are substantially similar in the present embodiment of my invention so that a description of one will make the system readily understood as well as the character of the process carried on thereby. The lower branch 16 of said pipe includes a hand valve 17, the housing 18 for a motor operated valve, the housing 19 for an expansion valve and another hand valve 20. Connected up with the hand valve 20, is a refrigerating coil 21, which is provided near its outlet end, with a thermostatic cylinder or chamber 22 from which a pipe 23 leads to a diaphragm housing 24 arranged above the valve housing 19. A positive main 25 is connected by a wire 26 to a thermostatic switch 27 which is operated by changing temperatures in the room containing refrigerating coil 21. A wire 28 leads from thermostatic switch 27 to one terminal of a motor contained in housing 29 which is disposed above the valve housing 18. A wire 30 connects the other terminal of said motor to a negative main 31. As shown in Figure 3, the motor in housing 29 is adapted to operate a shaft 32 which carries an eccentric cam 33. Said cam 33 is suitably disposed to operate a ball valve 34 which is pressed upon by the head 35 of a stem 36 which is reciprocably mounted in a spider 37, a spring 38 being interposed between said head 35 and spider 37 for exerting this pressure. Said valve stem 36 is provided at its other end with lugs 39 which serve to hold that end central to the bore of the pipe 16. The balanced pressure valve is shown in its preferred embodiment in Figure 4. Thus the valve housing 19 is provided with an inlet port or opening 40 into which opens the pipe section 16 leading from valve housing 18. A passage 41 leads from the opening 40 to a valve port or opening 42 which is presented downwardly. A valve point 43 is adjustably mounted in a reciprocable plunger 44, a diaphragm 45 being secured between its upper end and the lower portion 44^a of a yoke which is yieldably mounted upon a slide or cross head 46 having threaded connection with a stem 47. The yoke 48 of which the lower portion 44^a

preferably constitutes an integral part, rests upon a spring 49 carried by the slide or cross head 46. Said plunger 44 is provided with an opening 50 which permits it 5 to be reciprocated by diaphragm 45. This opening 50 is in open communication with valve port 42 whenever valve 43 is retracted. The main chamber 51 in valve housing 19 has open communication by means of a port 52, 10 with a channel 53 which leads to hand valve 20 and refrigerating coil 21. It will be understood from Figure 4 that the pipe 23 transmits fluid pressure from thermostatic chamber 22 to an inlet port 54 which opens 15 into the diaphragm chamber above the diaphragm 45. Said diaphragm is therefore subjected on one side to pressure obtaining in thermostatic chamber 22 and on its other side to the pressure existing in refrigerating 20 coil 21. A balanced pressure control is thereby obtained which enables the system to be regulated with extreme nicety and made to operate with a high degree of efficiency. As shown in Figure 1, a line wire 55 leads 25 from the positive main 25 to a branch wire 56 which includes a fuse 57, an overload switch 58, and a high pressure cut-off switch 59. A resistance 60 is also connected up in this branch line in series with one 30 terminal of a solenoid 61, the other terminal of said solenoid being connected by a wire 62 to another wire 63 which is connected to a back pressure switch 64. Said switch 64 is adapted, under conditions to be pres- 35 ently described, to cover a contact 65 which is connected by a wire 66 to another wire 67 leading to the negative main 31. Whenever this circuit is closed, the solenoid 61 becomes energized and lifts a plunger 68 which car- 40 ries a bridge contact 68' which closes a gap between a contact at the end of wire 62 and a contact 69 which is connected by a wire 70 to the wire 67. A maintaining circuit for solenoid 61 is thus established which 45 does not include the back pressure switch 64. At the same time, a bridge contact 71 which is also moved by the plunger 68, is moved into position to close a gap in the main energizing circuit of motor 1. After 50 motor 1 has been running for a period of time, conditions in the system will be changed in such a way that the back pressure switch will be moved from contact 65 so that the maintenance of the motor 55 energizing circuit will depend alone upon solenoid 61. Eventually said contact 64 will be moved sufficiently to cover a contact 74. This closes a shunt circuit from line wire 55, including fuse 57, switches 58 and 60, 59, resistance 60, a resistance 72, wire 73, contact 74, switch 64, wire 63, wire 62, bridge contact 68, wire 70 and wire 67. Solenoid 61 is thereby short circuited, the 65 plunger 68 drops, and the motor comes to rest. Leading from each of the refrigerat-

ing coils 21, is a pipe 75 which is connected to a return pipe 76 which leads back to the compressor cylinder 9. A branch elbow 77 is connected to the return pipe 76 and at its upper end opens into a dia- 70 phragm housing 78. As shown in Figure 2, said elbow 77 opens upwardly into a chamber 79 below a diaphragm 80. A plunger 81 is provided with an enlarged head 82 which bears against the diaphragm 80 75 under the pressure of a compression spring 83, which is interposed between a collar 84 and a fixed guide 85. Near its lower end, said plunger is provided with a recess or opening 86 into which extends the shorter 80 arm 87 of the back pressure switch lever which is pivoted at 88. The longer arm 89 of said switch lever carries the back pressure operated switch 64. Interposed be- 85 tween the lever arm 89 and diaphragm 85 housing 78, is a spring 90 which causes the lever arm 87 to maintain a downward pres- 90 sure on the plunger 81. Whenever the contact 64 is brought into engagement with contact 65 for setting up the motor operat- 95 ing circuits, it is held in circuit closing position by means of a magnet 91 which is connected up in the conductor 66. In a similar manner, a magnet 92 is connected up in the conductor 73 for holding the contact 64 in 95 engagement with contact 74 until dia- 100 phragm 80 is forced upwardly.

In the operation of this improved system, let it be assumed that the compressor is at rest and that all refrigerating rooms 100 have become warmed up sufficiently to permit the thermostatic switch 27 to close. An energizing circuit being closed through 25, 26, 27, 28, 29, 30 and 31, motor valve 34 is opened. By reason of the slightly heated 105 suction end of the refrigerating coil, the pressure of fluid in thermostatic chamber 22 has over-balanced the pressure of fluid in the refrigerating coil so that diaphragm 45 has been depressed and valve 43 opened. Hand valves 17 and 20 being opened, the receiver 13 is in open communication with refrigerating coil 21. Diaphragm 80 being 110 moved upwardly by the back pressure in pipe 76, spring contact 64 is brought to 115 bear on contact 65 and the motor is started by the circuits pointed out above. The pumping action which is thus set up, is continued under normal conditions until the back pressure in pipe 76 drops sufficiently, 120 after all of the ammonia circuits have been cut off, to permit diaphragm 80 to be de- 125 pressed and the contact switch 64 to come into engagement with upper contact 74. This stops the motor by short circuiting the solenoid 61 and permitting bridge contact 71 to break the motor energizing circuit. It will be understood from the foregoing description that in addition to the 130 control of refrigerant by means of the mo-

tor operated valve 34 which depends upon temperature conditions in the room which contains or is cooled by the refrigerating coil or coils 21, there are several other co-operative controls. After the refrigerating process has been sufficiently extended in any coil, the temperature condition produced thereby, reacts to automatically disconnect that coil from the system so that the supply of refrigerant is then economized for any remaining coils that may be requiring a supply or, if all the coils are automatically cut off, it is held in reserve for future needs in any of the coils in the system. On the other hand, in order to secure a more sensitive control of the refrigerating fluid supply for maintaining the entire superficial area of the refrigerating coil as an active cooling surface, the expansion valve is made to depend upon the relative pressures of the fluid in said refrigerating coil and in the thermostatic chamber 22 which surrounds the last section of said refrigerating coil. The operation of the compressor 9 is under the control of pressure variations within the return pipe 76 of the system itself. Whenever a room reaches the lower temperature for which its thermostat is set, the motor valve is moved to closed position for shutting off the corresponding coil 21. The action of the compressor is thereupon further accentuated in reducing the back pressure in the return pipe 76. When the lower limit for which the back pressure regulator has been set, is reached, the compressor is stopped and remains idle until the back pressure has again risen sufficiently to set the compressor into action. It will be seen therefore that the refrigerating process varies with the general thermostatic condition in the room, with the thermostatic conditions immediately surrounding the warmest portion of the refrigerating coil and with the back pressure conditions in the system itself within the return pipe 76 which leads to the compressor. It will furthermore be understood that a variation in any of these elements serves to modify the operation of the other elements in such a way as to economize the consumption of power while at the same time concentrating the power where most needed. In practice it takes considerable time for the back pressure to build up sufficiently to start the compressor into action unless one or more of the rooms have warmed sufficiently to open up their motor valves. There would seem to be no limit to the expansion of this system which lends itself to arrangements of rooms and circuits in parallel, in series, or partly in parallel and partly in series. For example a number of small rooms or coils may be put into series for one circuit when it is not so important to hold them at accurately established tem-

peratures, the circuit for this series being placed in parallel with other circuits. Furthermore one or more compressors may be used in parallel between the suction line and the condensers. 70

The term "refrigerating coil," as used in the specification and claims, is intended to have the meaning usually understood in this art, namely, a single coil, or a plurality of coils operating as one coil in effect. 75

I claim:

1. In an automatic refrigerating system in combination, a compressor, a plurality of refrigerating coils, a supply pipe leading from said compressor and having a connection to each of said refrigerating coils, a shut-off valve and an expansion valve at the inlet end of each of said refrigerating coils, thermostatic means located in proximity to each refrigerating coil for controlling the 80 shut-off valve connected thereto, thermostatic means located at the outlet end of each refrigerating coil for controlling the expansion valve connected thereto, a common return pipe connecting the outlet ends of said 85 refrigerating coils to said compressor, and means controlled by the pressure in said return pipe for controlling the operation of said compressor. 90

2. In an automatic refrigerating system, a compressor, a plurality of refrigerating coils, a supply pipe leading from said compressor having a connection to each of said refrigerating coils, a shut-off valve, and an expansion valve at the inlet end of each of 100 said refrigerating coils, thermostatic means located in proximity to each refrigerating coil for controlling the shut-off valve connected thereto, a common return pipe connecting the outlets of said refrigerating coils 105 to said compressor, and a pressure responsive device in said common return pipe for controlling the operation of said compressor.

3. In an automatic refrigerating system, a compressor, a plurality of refrigerating coils, a supply pipe leading from said compressor having a connection to each of said refrigerating coils, a motor-operated shut-off valve and an expansion valve at the inlet end of each of said refrigerating coils, 110 thermostatic means located in proximity to each refrigerating coil for controlling the motor-operated shut-off valve connected thereto, a fluid pressure chamber surrounding a portion of each refrigerating coil near 115 its outlet end and operably connected to the expansion valve at its inlet end for controlling the supply of refrigerant according to the temperature in said fluid pressure chamber, a common return pipe connecting 120 the outlets of said refrigerating coils to said compressor, and a pressure responsive device in said common return pipe for starting said motor at a predetermined maximum 125 pressure and stopping said motor at a pre- 130

determined minimum pressure in said return pipe.

4. In an automatic refrigerating system, a compressor, a plurality of refrigerating coils, separate supply pipes and a common return pipe connecting said compressor and said refrigerating coils, a shut-off valve and an expansion valve in each of said separate supply pipes, a pressure responsive device located in said return pipe, a switch arm operated by said pressure responsive device, two spaced contacts adapted to be covered separately by said switch arm at different pressures in said return pipe, a motor for driving said compressor, an energizing circuit for said motor, a switch in said energizing circuit, a solenoid for operating said switch, an energizing circuit for said solenoid coil including said switch arm and one of said spaced contacts for starting said motor at a predetermined pressure in said return pipe, a shunt circuit connected across said switch arm and said spaced contact for maintaining the energizing circuit of said solenoid when said switch arm is out of contact with both of said spaced contacts, a switch in said shunt circuit operated by said solenoid simultaneously with the switch in the said motor energizing circuit, and a second shunt circuit connected across the terminals of said solenoid coil and including said switch arm and the second of said

spaced contacts for stopping said motor at another predetermined pressure in said return pipe.

5. In an automatic refrigerating system, a compressor, a plurality of refrigerating coils, separate supply pipes and a common return pipe connecting said compressor and said refrigerating coils, a shut-off valve and an expansion valve in each of said separate supply pipes, a pressure responsive device in said return pipe, a switch arm operated by said pressure responsive device adapted to contact with a fixed contact at a predetermined maximum pressure and adapted to contact with a second fixed contact at a predetermined minimum pressure in said return pipe, a motor for driving said compressor, an energizing circuit for said motor, a switch in said energizing circuit, a solenoid for operating said switch, an energizing circuit for said solenoid coil including said switch arm and the first of said fixed contacts, a shunt circuit connected across said switch arm and the first of said fixed contact, a switch in said shunt circuit operated by said solenoid simultaneously with the switch in the said motor energizing circuit, and a second shunt circuit connected across the terminals of said solenoid coil including said switch arm and the second of said fixed contacts.

ALBERT T. MARSHALL.
